Taiwan IPO Search Report issued in Taiwan Design Patent Application No. 109301211, dated Aug. 24, 2020 and English translation thereof (2 pages).

Primary Examiner — Paula Allen Greene

(74) Attorney, Agent, or Firm — Ferguson Braswell
Fraser Kubasta PC(57) **CLAIM**

The ornamental design for a communications headset, as shown and described.

DESCRIPTION

FIG. 1 is a back-right perspective view of a communications headset showing my new design;

FIG. 2 is a front-left perspective view thereof;

FIG. 3 is a right-side view thereof;

FIG. 4 is a left-side view thereof;

FIG. 5 is a back view thereof;

FIG. 6 is a front view thereof;

FIG. 7 is a top view thereof; and,

FIG. 8 is a bottom view thereof.

The broken lines are for the purpose of illustrating portions of the article and form no part of the claimed design.
